UNITED STATES PATENT OFFICE.

GEORGE E. PRYOR, OF LOS ANGELES, CALIFORNIA.

EXPANDING DEVICE FOR SPECTACLE-RIMS.

1,254,274.

Specification of Letters Patent. Patented Jan. 22, 1918.

Application filed March 6, 1917. Serial No. 152,885.

To all whom it may concern:

Be it known that I, GEORGE E. PRYOR, a citizen of the United States, residing at Los Angeles, in the county of Los Angeles 5 and State of California, have invented a new and useful Expanding Device for Spectacle-Rims, of which the following is a specification.

My invention relates to a device used for 10 the purpose of expanding spectacle rims of the class generally known as composition rims, that is, rims made of celluloid composition, and similar materials. It frequently happens that the lens is a little large for the 15 standard sizes of rims, which necessitates a cutting down of the lens, or an expansion of the rim.

The principal object of my invention is 20 to provide a simple form of expanding device by means of which composition rims may be expanded to fit the lenses upon which they are to be used.

Referring to the drawings, which are for 25 illustrative purposes only:

Fig. 1 is a side elevation of a device embodying a form of my invention.

Fig. 2 is a vertical section of the device shown in Fig. 1.

Fig. 3 is a sectional plan view on line 3—3 30 Fig. 1.

Fig. 4 is a sectional, plan view of a modified form of my invention, and

Fig. 5 is a side elevation of another modified form of my invention.

11 designates an outer member consisting 35 of a sheet metal mandrel in the form of a truncated cone, the upper end of which is closed by means of an end wall 12 formed as a part thereof. 13 designates a cylindrical inner member, preferably made of sheet metal, open at the top and having its lower end flanged outwardly, as indicated at 14. The outer edge of the flanged portion 40 14 fits within the lower end of the mandrel 11, as clearly shown in Fig. 2. Fitting within the lower end of the inner member 13 is a hollow stem 15 which is secured 45 therein in any suitable manner, as by brazing. The lower end 16 of the stem 15 is

threaded into a handle 17 of any suitable 50 material, the handle 17 having an opening 18 extending therethrough in open communication with the hollow stem 15.

20 designates a block of insulating material, such as fiber, the outer ends of which 55 extend through openings 21 formed in the

inner member 13 against the mandrel 11. 22 designates a screw which extends through the upper end of the mandrel into the block 20, thereby securing the mandrel against the 60 end of the inner member 13 and holding the same firmly in place. The block 20 is provided with a groove 23 on each side thereof connecting with a passage 24 extending diagonally through the block to the bottom 65 thereof. The inner member 13 constitutes a support for the heating element, which consists of a coil of exposed wire 25 wound upon insulating material, such as isinglass 70 27, which is placed around the inner member 13 and supported thereon. The ends of the wire 25 are passed into the grooves 23 in the sides of the block 20, thence downwardly through the passages 24 therein, being brought together under the block 20 and 75 twisted together, in which form they extend downwardly through the member 13, the stem 15, and the opening 18 in the handle 17, to any suitable source of electric current, the twisted portion of the wire being covered 80 with insulation of any common form, as indicated at 28. The heating coil is spaced apart from the mandrel, the mandrel being retained in such position by the ends of the block 20 and the flange 14 of the inner 85 member.

The device is used in the following manner:

Electric current is supplied to the wire 25 from any exterior source, not shown, there- 90 by heating the coil on the inner member 13, which imparts heat to the mandrel 11. The spectacle rim 30 to be heated is slipped on the mandrel, and as the same becomes heat- 95 ed, and expands, it may be moved downwardly upon the mandrel until the rim has been expanded to the desired size, standard sizes being indicated, if desired, upon the exterior of the mandrel, as indicated by the scale 31 shown in Fig. 1 of the drawings. 100 When the rim has been enlarged to the size desired, it may be removed from the mandrel and the lens inserted in the rim, the rim cooling and forming a tight fit on the lens. 105

While in Figs. 1, 2 and 3 I have shown a mandrel of circular form, it is understood that the mandrel and the heating element may be elliptical in form, as shown at 33 and 34 respectively in Fig. 4, and further that instead of having a handle, as shown in Figs. 1 and 2, for supporting the device, the 110

same may be placed upon a stand, as indicated at 35 in Fig. 5.

While I have referred to and called my invention an expanding device for spectacle rims, it is understood that I do not limit my invention to articles classified as spectacle rims, but that the same may be used for any form of eye-glass rims as well as other circular or elliptical shaped articles.

19 10 What I claim is:—

1. An expanding device comprising a tapered mandrel, an inner member within said mandrel, means for securing said mandrel to said inner member, a heating element on said inner member, and handle means secured to said inner member for supporting said device.

2. An expanding device comprising a frusto-conical mandrel, a cylindrical member within said mandrel, an electric heating element on said cylindrical member, means for insulating said heating element from said cylindrical member, means for securing said mandrel to the cylindrical member, and means for supporting said cylindrical member.

25 3. An expanding device comprising a ta-

pered mandrel, a cylindrical member within said mandrel, a block of insulating material supported in said cylindrical member having 20 passages therethrough, means engaging said block for securing said mandrel to said cylindrical member, insulating material on said cylindrical member, a coil on said last named insulating material, the ends of said 35 coil extending through the passages in said block, and means for supporting said cylindrical member.

4. An expanding device comprising a tapered mandrel, a cylindrical inner member 40 spaced apart from said mandrel, a flange on the lower end of said inner member engaging the lower edge of said mandrel, a block of insulating material supported in said inner member, an end closure on said mandrel, 45 means on said mandrel engaging said block for securing said mandrel to said inner member, a heating coil supported on said inner member, and a handle support for said inner member.

In testimony whereof, I have hereunto set my hand at Los Angeles, California, this 23d day of Feby., 1917.

GEORGE E. PRYOR.
